UNITED STATES PATENT OFFICE.

DEXTER B. GRAY, OF KINGSVILLE, TEXAS, ASSIGNOR TO BOWEN CAR INITIAL & NUMBER RECORD CO., OF KINGSVILLE, TEXAS.

RECORD-PRINTING DEVICE.

1,372,501.

Specification of Letters Patent. Patented Mar. 22, 1921.

Application filed June 25, 1920. Serial No. 391,627.

To all whom it may concern:

Be it known that I, DEXTER B. GRAY, a citizen of the United States, residing at Kingsville, in the county of Nueces and State of Texas, have invented certain new and useful Improvements in Record-Printing Devices, of which the following is a specification.

This invention relates to record printing devices of the kind shown in Letters Patent of the United States No. 1,094,298, granted Apr. 21, 1914, to Carl R. Bowen, of Haileyville, Oklahoma. This patent shows a device for use on cars by passengers or men of the crew to print in a quick and easy manner a record indicating the number of the car and other such data.

The object of the present invention is to provide a device of the same general kind as that shown in said patent, but which is of improved construction, being more easily and economically made, more durable, better protected from the weather, more conveniently operated and which is provided with means of gaging the card or sheet of paper when moved to printing position.

In the accompanying drawings:—

Figure 1 is a perspective view of my improved record printing device applied to the side of a car.

Fig. 2 shows a vertical section on the line 2—2 of Fig. 1.

Fig. 3 shows a transverse section on the line 3—3 of Fig. 2.

Fig. 4 is a detail view of the lower portion of the device with parts broken away, indicating how the sheet or card is inserted in the device.

Fig. 5 is a perspective view of a portion of the die carrier.

Fig. 6 is a perspective view of a portion of the combined printing and cutting die.

The casing A is preferably made of sheet metal, the front *a* and the back *a'* being in one piece, bent to provide the top *a''*. The back *a'* extends to the bottom of the device, while the front *a* terminates a considerable distance above the bottom, being bent at *a''* and continued a short distance below the bend. The housing B for the printing device is preferably also made of sheet metal. It is closed at top, bottom, opposite ends and at the front and is open at its inner end. It has a flange *b* which is overlapped by the

lower front portion of the casing, as indicated in Fig. 2, and it is formed with a downwardly extending part *b'* which reaches to the bottom of the device.

At each end of the casing A there is a strip C, preferably of wood. These two strips serve to hold the front and back of the casing a suitable distance apart, and the casing is secured to these strips by fastening devices *c*. In this way a space is provided in the casing for the reception of cards or sheets of paper. The housing B is also secured to the strips C by fastening devices *c'*. In this way a weather-proof casing is provided, open only at the bottom as indicated at *x*.

Within the housing B there is a die carrier D, provided with a pin *d* extending through an opening in the front of the housing. This pin may be called a push pin although it is intended usually that it be struck by a hammer or other suitable tool, to operate the die.

The die carrier is yieldingly held in a retracted position by springs E set in sockets *e* in the die carrier and bearing against the strips C.

By bearing or striking on the pin *d* the die carrier may be forced inward against the force of the springs.

As shown in Fig. 5, the die carrier is formed with a dove-tailed socket *d'* to receive the die G which carries the printing devices *g* and the cutters H. There is a cutter H at each end of the die and preferably each cutter is of T-form and the cutting edges are disposed above or beyond the plane of the printing devices. The part *h* of each cutter is disposed longitudinally of the die and the part *h'* at right angles to the part *h*.

It will be observed by reference to Fig. 4 that the strips C are cut away at their lower ends and shoulders *c''* are formed therein. When a card or sheet S is first inserted, a number of numbers or other indications are formed at the top of the card or sheet when the die is operated and at the same time a corner is cut from the card or sheet on each side, as indicated at *s*. When the printing device is retracted and the card is moved farther inward its movement is limited by the shoulders *c''* which serve to position the card or sheet in such manner that the next inward movement of the printing device

will effect the printing in a space below the first line of print. In this way double printing or blurring of the record is prevented.

Each time a printing operation is performed corners are cut from the card or sheet and thus a series of lines may be printed in proper order if desired.

The cutters are of such form that the card or sheet comes in contact with the cutters at the points y , as indicated in Fig. 6.

It is the custom in order to identify cars, to make a memorandum of the name of the railroad, the number of the car, and the weight of the car. This is done by someone assigned to such duty, usually with a pencil in a memorandum book or on slips of paper. It is often done under unfavorable conditions, such as darkness, rain, windy weather, and the like, and often mistakes are made and a car with perishable goods is lost by reasons of such mistakes, the contents of the car are destroyed and the railway company often stands the loss. The device above described is intended to remedy these troubles. Each car is provided with one of these devices. The printing device carries a die with the initials of the railway, such as ERR, indicated in Fig. 4, next the number of the car, such as 1456, and next the weight of the car and contents, such as 125770 indicated in Fig. 4. The printing die may be supplied with ink in any suitable way or it may merely indent the numbers in a card or slip of paper, but preferably a sheet of carbon paper is employed and inserted with the card or slip so that a carbon impression is made on the slip. It will, thus, be seen that the person having the duty of taking the information can very easily obtain the necessary record. Each car, as before stated, carries a printing device indicating the name of the railroad, the number of the car, and the weight of the car and contents, the figures indicating the weight being adjusted when the car starts on its journey. Thereafter at any time a record may be taken in the manner before explained.

I claim as my invention:—

1. A printing device, comprising a casing closed at the top and having an opening at its lower end through which a sheet to be printed may be inserted, and which comprises a back part and a front part which is of less length than the back part and is formed with a shoulder near one end, a housing projecting sidewise from the front of the casing and opening thereinto and which is provided with a flange engaging the shouldered portion of the front of the

casing and with a flange projecting in an opposite direction to the lower end of the casing, a die carrier operating in said housing, a pin for operating the die carrier, and springs for returning the die carrier to normal position. 65

2. A printing device, comprising a casing having an opening at its lower end into which a sheet to be printed may be inserted, a die carrier, a housing for the die carrier projecting laterally from the casing and opening thereinto, springs for returning the die carrier to normal position, a printing device mounted on the die carrier, and a cutter at one end of the printing device and 70 carried thereby for cutting a notch in the corner of the sheet during the printing operation, said casing being provided with a shoulder at one side with which the notched portion of the sheet engages when the sheet 75 is moved vertically into the casing.

3. A printing device, comprising a sheet metal casing having integral back and front parts connected at the top by an integral part of the metal, strips closing the opposite sides of the casing and secured thereto, a sheet metal housing detachably connected with the casing and secured to said side strips, a die carrier mounted within the casing, a pin extending through the casing for 85 operating the die carrier, and a combined cutter and die removably mounted in the die carrier.

4. A printing device, comprising a casing, a housing connected therewith, a die carrier mounted in the housing, means for operating it, a die mounted in the carrier provided with printing devices, and a cutter at one end of the printing device and carried thereby for forming a notch in the 95 sheet to be printed during the printing operation, said casing being provided on one side with a shoulder with which the notched portion of the sheet engages when moved 100 into the casing. 105

5. A printing device, comprising a casing, a housing connected therewith, a die carrier within the housing, means for operating the die carrier, a printing die mounted on the carrier, and a T-shaped cutter at one end of the printing die and carried thereby for forming a notch on the sheet on which the record is made, said casing being provided on one side with a shoulder with which the notched portion of the 110 sheet engages when the sheet is moved into the casing. 115

In testimony whereof, I have hereunto subscribed my name.

DEXTER B. GRAY.
